CARD PUNCHING MECHANISM

Gustav H. Kroeger, Herkimer, N. Y., assignor to Remington Rand Inc., Buffalo, N. Y., a corporation of Delaware

Application February 18, 1938, Serial No. 191,179

5 Claims. (Cl. 164—112)

This invention relates to statistical card punches and more particularly relates to structural means for efficiently operating parts thereof.

Statistical card punches similar to the structure herein described, have been disclosed in numerous patents, such as No. 1,985,101 of December 18, 1934, or No. 2,044,208 of June 11, 1935, both to W. W. Lasker. Copending patent application Serial No. 104,391, filed by Lasker also discloses the general type of punch structure to which this invention may be adapted.

In many applications of punched cards, particularly those which classify and tabulate freight cars and car loading data, it is convenient to employ a means of cancelling only certain data after punching a card, leaving a portion of the data such as the date, destination, etc., ready for punching in the next and succeeding cards. There are means at the disposal of the operator for doing some selective cancelling on the present machines but the structure herein to be described is more comprehensive and better adapted to the existing problems.

The device consists of a hand-operated push bar which actuates a lever having contact with some of the first row set pins, forcing them down in unison when the bar is operated. An adjustable collar is provided on the push bar, which limits the motion of the bar and lever so that the set pins are forced down only far enough to unlatch all pins in the field leaving it clear for another set-up.

The object of this invention is to provide a means for selective cancelling of specified data in a statistical card punch.

Another object is to provide a cancelling means which is hand-operated and entirely independent of any other punch operation.

Another object is to provide a structure for cancelling data in set fields when the fields are not adjacent to each other.

Other objects and structural details of the invention will be apparent from the following description when read in connection with the accompanying drawings, wherein:

Fig. 1 is a fragmentary front elevation of a card punch showing the operating handle of the new device;

Fig. 2 is a cross sectional view of the left-hand side of a card punch showing the erase mechanism in more detail;

Fig. 3 is a rear view of a portion of the setting carriage showing the erasing lever;

Fig. 4 is a detailed sectional view showing the action of the erasing lever and set bars.

Fig. 5 is a plan view of the erasing mechanism; Fig. 6 is a plan view of a modified form of the erasing plate member.

The card punch shown in Fig. 1 consists of a frame 10 upon which are mounted the several parts of the punch assembly. The motor-generator 11 supplies both mechanical and electrical power to operate other parts of the mechanism. A clutch assembly 12 operates the carriage return, backspace and punching operations. A keyboard 13 is provided which contains the keys necessary for controlling the set-up of the data to be transferred to the card. These keys operate switch contacts beneath the key panel and thereby control a series of solenoids 14 which by means of Bowden wires 15, communicate the motion of the solenoid armatures to the levers 16 on the setting carriage 17. In this type of punch, the cards are not perforated until the entire data set-up has been made. Then this punching operation is accomplished in a single die movement. The set-up is first made by the setting carriage 17, which is progressively spaced longitudinally of the machine as the data is transferred to a field of set bars 20 interposed between the punches 21 and the setting carriage.

The punches 21 are mounted in plates 19 and 19a and extend through a plate 22 which together with die plate 18 form a card chamber. The plates 22 and 19a with the die plate 18 are secured together to form a unitary structure which is capable of being raised by a cam (not shown) through the action of arm 18a. Each of the above plates including the die plate contain 540 holes in which the punches 21 are positioned in 45 rows of 12 pins each. The tops of the punches 21 are provided with an enlarged head to prevent them falling through the plate 19.

The field of set bars 20 consists of 540 bars, one of which is located directly above each punch. The bars are held in position by suitable guide plates and urged upwardly by springs 23, (Fig. 4). When a set bar is depressed by a lever 16 on the setting carriage 17, an extrusion 24 formed on each set bar, engages the inclined surface of a cam face 25 formed in a locking slide 26, forcing the slide to the left (Fig. 4) until the extrusion 24 has passed beyond the edge of the cam at which time the locking slide is free to move into its original position thereby locking the bar depressed. A flat spring 27 urges the locking slides to the right (Fig. 4) with the result that the set bar is held down in its depressed position until released by the operation of a second set-bar in the same column.

After the data has been entered in the set bar field, the machine is ready for punching a card. The feed rollers 28 feed a card from a supply stack in the magazine 30 to the card chamber and held therein by a card stop 50. The plates 19a, 5 22, and 18 are then lifted upwardly, forcing the punches against the set-bars which have been latched down thereby punching a hole in the card in those positions. In positions where the 10 set bars have not been latched, the punches are lifted by the card and no perforation results.

When the punching operation is finished, the card stop 31 is lowered and the card is fed out of the card chamber. The carriage is returned to its initial position at the left-hand end of the set bar field (Fig. 1) and the machine is ready to set up data for the next card. When the card is to contain data which is totally different from the preceding one, the trip key is depressed and a card is punched with the return of the carriage 15 and a cancellation of all the data previously set up. When, however, a large part of the data for one card is to be repeated on the next, and only a small portion changed, it is convenient to erase 20 only that part which is to be changed and retain the rest. This may be done with the present machines by depressing the card, carriage return key which punches a card, returns the carriage, but 25 does not cancel the set-up.

Heretofore the carriage was moved to that part 30 of the field where the new data was to be substituted for the old, and the erase key depressed for each character to be removed. The carriage was then moved back to include the same field 35 and the new data set up as previously described. While this method is more convenient than setting up the entire card, it may be improved upon by the erase mechanism which will now be described.

A shaft 32 (Figs. 3, 4 and 5) is mounted in the 40 brackets 33 and 34 secured to the frame 35 of the set bar basket. Secured to the shaft 32 is a lever 37 and a plate 38. The plate 38 is positioned above and adapted to engage the first 45 set bars 20 corresponding to the 12 position of a predetermined field of the card.

Formed on the lower end of lever 37 is a fork 39 the arms of which are slotted to engage a pin 40 which is set into the end of a push rod 41. The push rod is slidably supported by two bearing 50 plates 42 and 43 one of which, 42 is formed with a boss having a set screw 44 therein which engages a flattened portion 45 of the rod and prevents it from turning. The other plate 43 forms 55 a stop for a collar 46 which limits the return movement of the rod, and also provides a bearing for a spring 47, which is adapted to hold the device in normal position. A suitable button or lever 48 is secured to the front end of the push 60 rod 41 to facilitate manual operation.

When it is desired to erase the data set upon the predetermined field the rod 41 is pushed in by pressing on button 48 thereby rocking the lever 37 in a clockwise direction (Fig. 2) thus rocking the plate 38 down to depress the associated bars 20. A full stroke of rod 41 which is determined 65 by the handle 48 rocks the lever 37 through a predetermined angle such that the set bar 20 associated therewith will cam the locking slide 26 to its extreme position shown in Fig. 4 where the extrusions of all bars which have been locked down will be free of the cam face thus permitting all actuated bars to rise.

When the button 44 is released the lever 37 70 returns to normal position and the associated

set bars return to their unlatched position, due to the fact that they were not depressed beyond the point of the cam 25. In this manner a single operation will erase all the data which had been set up in certain columns of the set 5 bar field.

It is not necessary to have the erase mechanism operate on a single area or field of set bars. By extending the plate 38 for the entire length of the set bar assembly and cutting out 10 specified portions 50 of the edge of the plate (Fig. 6), any number of areas may be erased by this device resulting in the elimination of any combination of data that had previously been set up.

The device is used in the following manner: 15 After a set-up as been completed, the card, carriage return key is depressed which punches the set-up data in a card and returns the carriage without cancellation. Then the button 48 is pushed in manually, erasing the predetermined 20 areas and the skip key is operated to bring the carriage to the first settable stop which has been placed at the beginning of the first erased field. The new data is then set into this field and the skip key again operated to position the carriage 25 at the beginning of the second erased field, and this procedure is continued until the data has been completely set. A card is then punched and the operation repeated as described for each additional card.

Besides the adaptation of this invention to freight car statistical work as hereinbefore mentioned, the device is well suited to department store accounting where a card is punched for each lot of merchandise received. When a number of similar lots is received, the cards, which must be punched to represent this material, contain a great percentage of identical data and considerable time is saved by setting up only the change of data rather than the entire card. In 40 some cases, this change in data is only a different lot number and the speed at which these cards are produced with this invention is measurably increased.

While I have described what I consider to be a 45 highly desirable embodiment of my invention, it is obvious that many changes in form could be made without departing from the spirit of my invention, and I, therefore, do not limit myself to the exact form herein shown and described, 50 nor to anything less than the whole of my invention as hereinbefore set forth, and as hereinafter claimed.

What I claim as new, and desire to secure by Letters Patent, is:

1. In a statistical card punch having a field of set bars capable of being latched into an operating position, the combination of a plate member, a lever member and a connecting rod, the said plate member being secured to the said lever 55 member and engaging the ends of a plurality of set bars, the said lever member being pivotally mounted and engaged by the said connecting rod whereby motion is communicated to the set bars causing their partial depression, said depression releasing all the set bars in a single coating column.

2. In a statistical card punch having a field of set bars capable of being locked in an operating condition, the combination of a pivoted lever, 70 a plate member which engages the upper ends of one row of said set bars and is secured to the said lever, and a manually operable connecting member which engages the said lever whereby the combination may be operated to partially de- 75

press the said row of set bars and unlock the set bars in said field.

3. In a statistical card punch having a column of set bars capable of being locked into operating condition by a locking slide and capable of being released by the partial depression of a single set bar, the combination of a pivoted lever, a flat plate secured to said lever and a push rod which engages said lever whereby the operation 10 of said push rod causes the said flat plate to engage, depress and unlatch a plurality of set bars.

4. In a statistical card punch having a field containing a plurality of columns of set bars capable of being latched into operating condition and capable of being unlatched by the partial depression of a single set bar in each column, the 15

combination of a pivoted lever with a flat plate secured to one end thereof and a push rod which engages with said lever whereby the operation of said rod causes the plate to engage and unlatch a plurality of columns of set bars. 5

5. In a statistical card punch having a plurality of columns in a field of set bars capable of being latched into operating condition and capable of being unlatched by the partial depression of a single set bar in each of said columns, the combination of a lever member and a push rod, the said lever member engaging a set bar in each of said columns of set bars at one end thereof and being pivotally attached to the push rod at the other end with means for manual operation. 10 15

GUSTAV H. KROEGER.
